UNITED STATES PATENT OFFICE

132,900

DESIGN FOR A HAIR CLIPPER BLADE

Roy Whitney, Decatur, Ill.

Application February 20, 1940, Serial No. 90,381

Term of patent 7 years

To all whom it may concern:

Be it known that I, Roy Whitney, a citizen of the United States and a resident of the city of Decatur, county of Macon, and State of Illinois, have invented a new, original, and ornamental Design for a Hair Clipper Blade, of which the following is a specification, and reference being had to the accompanying drawing, forming a part thereof.

Fig. 1 is a bottom perspective view of a hair clipper blade showing my new design.

Fig. 2 is a top perspective view;

Fig. 3 is a top plan view; and

Fig. 4 is an end view thereof.

I claim:

The ornamental design for a hair clipper blade, as shown.

ROY WHITNEY.
